UNITED STATES PATENT OFFICE.

HERMAN G. PAPE, OF NEW YORK, N. Y.

TELEPHONE INSTRUMENT.

1,236,103.

Specification of Letters Patent. Patented Aug. 7, 1917.

Application filed November 27, 1914. Serial No. 874,234.

To all whom it may concern:

Be it known that I, HERMAN G. PAPE, a citizen of the United States, and resident of New York, in the county of New York and State of New York, have invented certain new and useful Improvements in Telephone Instruments, of which the following is a specification.

My invention relates to phonetic instruments adapted for use as telephone transmitters, microphones, or audiphone receivers, or analogous purposes.

An object of the invention is to provide an instrument of this class which will be sensitive and at the same time durable, and which may also be manufactured in large numbers with little or no variation in the sensitiveness, accuracy, and uniformity of the instruments.

20 The invention comprises various features of construction contributing to this general object.

A main casing, comprising a body and a front piece or cap threaded thereon, forms 25 a housing for the microphone and the main diaphragm. The said diaphragm is preferably made of glass and supported by its periphery in an annular recess formed in the casing and its cap, said recess being of sufficient width to receive packing rings or 30 gaskets made of paper or other suitable material. These packing rings hold the diaphragm with moderate elastic pressure permitting freedom of vibration, and also act 35 as a mechanical buffer to prevent breakage of the diaphragm when the instrument is subjected to jars or strain. The packing also acts as a sound insulator or deadener to confine the mechanical vibrations to the diaphragm, eliminating sounds due to the resonance of the casing so that the electrical 40 impulses into which the sound vibrations are transformed, represent more faithfully and accurately the voice or other sounds it is desired to transmit.

The front piece or cap overlying the diaphragm is formed with a group of perforations which are compactly arranged opposite the center of the diaphragm to concentrate the sound waves on the central portion 50 of the diaphragm where they are most effective, and to further effect such concentration the inner surface of the perforated plate is dished or concave, which not only 55 reduces the thickness of said plate at the center, thereby reducing the resistance to

the transmission of the sound waves through said openings, but also operates in a measure to focus or deflect toward the center of the diaphragm, the sound waves reflected on the 60 concave surface.

The microphone button comprises a cylindrical body or casing, the outer periphery of which is threaded to enter a threaded opening in the back of the main casing, a 65 flange on the said periphery forming a stop or gage to accurately position the microphone button within the main casing.

The cylindrical microphone casing is provided at a position intermediate its front 70 and rear faces with a partition wall formed with a cylindrical opening in which an electrode is mounted. With this arrangement the electrode may be accurately adjusted forwardly or rearwardly to bring its front face 75 to the exact position desired, and the electrode then secured in the adjusted position by soldering or otherwise. The front electrode may be supported by a diaphragm, preferably of mica, the latter having its periphery seated in an annular recess formed by the microphone casing and a ring threaded on to the casing. The carbon particles forming the resistance varying medium between the electrodes, are held in position by 80 a suitable soft elastic insulating material, such as zephyr or other yarn surrounding the electrodes and forming a packing or filling in the space between the mica diaphragm and the rear wall of the microphone casing. 85

The front or swinging electrode may be provided with a forwardly projecting roughened stem protruding through a central opening in the glass diaphragm but out of direct contact with the diaphragm, and connected to the diaphragm by means of a drop of cement or other suitable material which may be applied in a liquid state and then allowed to harden. This method of connecting the diaphragm and electrode permits the 90 parts to be accurately adjusted and then securely connected without any disturbance of the adjustment and without placing any strain on any diaphragm such as occurs with the usual methods of connecting swinging 100 electrodes.

A protector plate attached to the back of the main casing, covers and protects the otherwise exposed conducting portions of the microphone, said protector plate also 110 constituting a wire or cord outlet for the microphone.

The casing may be provided with projections or buttons at intervals around its periphery to prevent the instrument from rolling when laid on a desk or other support. This feature is of special value when it is desired to use the instrument on a table and it is made in double form as shown, for example in my Patent #1,025,992.

A further object is to provide an instrument that shall be very light in weight and at the same time strong and durable.

Other features and advantages will appear hereinafter.

The present application discloses an improved means for preventing the instrument from rolling when placed on a flat table or support, which means is shown and claimed in my co-pending application, Serial No. 80,874, filed February 28, 1916.

In the accompanying drawings,—Figure 1 is a sectional elevation view of an instrument constructed in accordance with the principles of my invention. Fig. 2 is a front view of the cap or front plate. Fig. 3 is a view of the protector plate. Fig. 4 is a sectional elevation view on a somewhat larger scale, of the microphone button and the glass diaphragm attached thereto. Fig. 5 is a view of the front electrode and the surrounding diaphragm. Fig. 6 is a sectional elevation of the microphone casing and the rear electrode mounted therein.

The main casing comprises a body 1 and a cap or front piece 2 threaded thereon to permit the cap to be set up solidly against the face of the body 1. The abutting faces of the body and cap may be formed with annular recesses to provide a groove 36 for the reception of the periphery of a diaphragm 27. The diaphragm preferably consists of a thin glass disk. A diaphragm made of glass or vitreous material is particularly adapted for the use in a telephonic transmitter as it is unaffected by atmospheric moisture or moisture from the breath, and is very elastic and possesses comparatively little inertia so that it is highly sensitive to sound vibrations. The diaphragm is supported at its periphery between rings or gaskets 29 of paper or other suitable packing material placed in the groove 36 on both sides of the diaphragm. These packing rings bear on the diaphragm with a moderate elastic pressure permitting a free vibration of the diaphragm, and also serve as a mechanical buffer to protect the diaphragm from jars or strains to which the casing may be subjected by falling or other rough usage.

The front plate or cap 2 of the casing comprises a central portion 32 provided with a set of openings 33 to permit the passage of sound waves to the diaphragm. The perforated portion 32 is surrounded by an annular boss 32^a which forms within the cas-

ing an annular chamber or recess 34. The chamber 34 may be termed a compression relief chamber as it acts as a capacity chamber to relieve the pressure of the sound waves confined between the diaphragm and cap 2. Compression relief or dissipating vents 35 extend from the chamber 34 through the casing to relieve the pressure in said chamber. Strengthening ribs 28 are formed on the inner face of the cap 2.

The walls of the openings 33 are flared or tapered as shown. A compact arrangement of the openings is provided for obtaining a large area of open space opposite the central portion of the diaphragm to permit a comparatively free passage of the sound waves and to concentrate the same on the central portion of the diaphragm where they are most effective. According to this arrangement of the openings 33, the central group comprises three openings close together, in the form of an equilateral triangle, the centers of the openings being at the angles of the triangle. Surrounding this central group is a second group comprising 12 openings also arranged in the form of a triangle having its sides parallel with those of the central triangle. Outside this second triangle are groups of openings, one group of two or more openings along each side of the triangle and arranged in rows parallel with the sides of the triangle. With this arrangement the center of the cap remains imperforate so that there is no opening directly in front of the stem 17 of the swinging electrode.

The microphone button comprises a supporting body or casing 5 in which are mounted a stationary or fixed carbon electrode 6 and an electrode 15 connected to vibrate with the main diaphragm 27. The support 5 is in the form of a cylinder and comprises a wall or web 38 provided with a circular opening in which the electrode 6 is mounted. The casing 5 is provided on its outer periphery with screw threads for connecting it with the back of the main casing 1 which is provided with a correspondingly threaded opening. An annular flange 41 is formed on the periphery of the casing 5, in position to bear against the back of the casing 1 and thereby form a stop or gage to accurately and definitely determine the position of the microphone button within the main casing. The opening in the partition 38 is provided with a flange 42 which may extend rearwardly and provides a suitable bearing for the electrode 6. Said flange and the outer rim of the casing form an annular recess 40. By means of this construction the electrode 6 may be accurately adjusted in the direction of its axis to bring its front face 39 to the exact position desired relative to the front electrode 15. An important advantage is thereby obtained

over the usual constructions in which the electrode is supported by its rear face bearing against a fixed wall or support. This advantage is due to the fact that it is practically impossible to obtain carbon disks or electrodes of uniform thickness, but they may be obtained of uniform diameter to fit within the cylindrical opening formed by the flange 42. These buttons may be 5 coated with copper and sweated into the brass casing 5 and additionally secured by a ring of solder 7.

The front electrode 15 may be mounted on a metal base plate 14 hollowed out and 15 from which projects forwardly a stem 17 having a threaded or roughened surface, said stem having a reduced neck 18 at its point of connection with the base. The electrode is carried in a circular mica dia- 20 phragm 12, secured to the electrode as by means of a threaded aluminum ring or nut 16. The diaphragm 12 is peripherally supported in an annular recess formed between the casing 5 and an aluminum ring 20 25 threaded thereon and bearing solidly against the front face of the casing. Packing rings 13 in said recess bear against the front and rear faces of the diaphragm. The construction and arrangement for supporting the 30 diaphragm 12 may be substantially the same as that set forth in connection with the main diaphragm 27 and its support.

With the arrangement described great accuracy and uniformity in positioning and 35 spacing the electrodes is obtained as the front face 39 of the electrode 6 may be accurately positioned by means of a suitable gage and then secured in such position in the manner hereinbefore set forth, leaving 40 the opposing faces of the electrodes exactly parallel and at a predetermined distance apart. The resistance varying medium comprising carbon granules 31 or other suitable material is held in position by means of a 45 resilient or soft packing 9 which may consist of a ring of zephyr, or other yarn or material possessing the requisite properties. Said packing fills the annular space between the mica diaphragm 12 and a mica 50 disk or ring 8 forming an insulating facing for the wall 38. The front electrode 15 is preferably of somewhat smaller diameter than the fixed electrode to prevent pressure of the packing material on its periphery 55 and thus permit a free swinging of the electrode.

The electrode 15 is fixedly connected with the glass diaphragm 27 by means of a mass, compound, or cement 30. In assembling the 60 parts, the stem 17 projects through a central opening in the diaphragm 27, but without touching the diaphragm. The connecting material 30 is preferably an alcoholic cement, or other suitable insulating mate- 65 rial which may be applied in a liquid state

and then allowed to harden. By this method of connecting the electrode with the main diaphragm, the accurate adjustment of the parts is not disturbed nor any strain placed on either diaphragm. At the same time a 70 solid reliable and permanent connection is obtained. This also forms a suitable means for connecting a diaphragm made of metal or other material than glass.

The cap 2 of the main casing is provided 75 at intervals around its periphery with buttons 37 which break the continuity of the circular bearing surface and thus prevent any material rolling of the instrument when supported by its periphery on a flat surface 80 as a desk or table. This means of preventing rolling is also applicable to various other forms of telephone receivers and the like.

A protector plate 3 may be secured as by means of screws 4 to the back of the casing 85 1 and covers and protects the otherwise exposed conducting parts of the microphone. The plate 3 also constitutes a wire or cord outlet for the conducting cords or wires which extend through an opening 25 in an 90 extension 24 providing a chamber 23 to contain split pin cord or wire tips. Said tips are received in sockets formed in terminals 21 secured in the main casing, said terminals connected by conductors 19 to the electrodes. 95 The protector plate 3 has a central recessed portion 26 reducing the thickness of the plate opposite the microphone. The plate 3 being recessed tends to prevent pressure being brought to bear near the center of 100 the plate when the instrument is supported on a person, and in various other conditions of use. Such central pressure would tend to distort the main casing carrying the electrode button. The recessed portion 26 also 105 provides a suitable space for printed matter or the like which it might not be desirable to place on the face of the instrument.

Modifications may be resorted to without departing from the spirit or scope of the 110 invention, and parts of the invention may be used without others.

What I claim as new and desire to secure by Letters Patent of the United States is,—

1. In a sound transforming instrument, 115 the combination of a thin circular glass dia- phragm, means surrounding the diaphragm and forming a peripheral support therefor, a microphone comprising an electrode hav- 120 ing a stem extending between the micro- phone and the diaphragm, and means form- ing a fixed connection between said stem and diaphragm, said means engaging a small area only at the center of the diaphragm, the remaining surface of the diaphragm 125 being exposed and free for sound waves to impinge thereon.

2. In a sound transforming instrument, 130 the combination of a glass diaphragm re- sponsive to sound vibrations, electro-respon-

sive means comprising an element vibratable in unison with the diaphragm, said element and diaphragm being separately supported in fixed positions in the instrument, and a connecting medium by which the said element is secured to the diaphragm, said medium consisting of a material which may be applied in a liquid state, preventing any tension or strain between the diaphragm and said element while the instrument is inactive, which material sets and forms a rigid unyielding connection between the diaphragm and said element.

3. In a telephone instrument, the combination with a diaphragm responsive to sound vibrations, said diaphragm having a central opening, of a resistance varying element, means to support said element in a fixed position in the instrument, a stem on said element having a roughened surface and extending into said opening out of direct contact with the diaphragm, and a connecting medium between said stem and diaphragm consisting of a homogeneous mass of material which may be applied in a liquid state, leaving the diaphragm free from strain or tension by said stem, and which material sets and forms an unyielding connection between the stem and diaphragm.

4. A telephone instrument comprising a casing having an approximately flat rear face wall formed with an opening therein, a microphone comprising an electrode disk mounted in said opening and forming a closure therefor, and a protector plate overlying said plate in close proximity thereto to limit the thickness of the instrument and secured to said casing and covering said microphone, said plate at one portion of its periphery projecting a short distance only beyond one edge of the casing and turned back to meet the casing so that said projecting portion of said plate forms a pocket to receive cord terminals without increasing the thickness of the instrument.

5. A telephone instrument comprising a casing, a resistance varying element therein rigidly mounted on the rear wall of the casing, and an insulating plate secured to the outside of said casing in position to overlie said wall, but spaced therefrom a slight distance only and forming a protector for said wall and resistance varying element and the electric conducting parts within the casing, said plate at one portion of its periphery, projecting a short distance only beyond one edge of the casing and turned back to meet the casing so that said projecting portion of said plate forms a pocket to receive cord terminals without increasing the thickness of the instrument, said pocket terminating in a round-lip cord outlet.

6. A telephone instrument comprising a casing having a back with an opening therein, a microphone button mounted in said

opening, and a thin protector plate secured to the outside of the casing in position to cover said back and spaced therefrom a slight distance only and protecting the otherwise exposed parts of the microphone, and also forming a cord or wire outlet for the conductors leading from the microphone, said plate having a central portion of reduced thickness set in from the surrounding portion of the plate.

7. A telephone instrument comprising a casing having a back with an opening therein, a microphone rigidly mounted in said opening, and a disk like protector plate secured to the outside of the casing in position to cover said back and spaced therefrom a slight distance only and protecting the otherwise exposed parts of the microphone, said protector plate having a peripheral extension projecting a short distance only beyond the periphery of the casing and providing a terminal chamber for cord terminals connecting with said conductors, without increasing the thickness of the instrument, the portion of the plate overlying the microphone being reduced in thickness and forming a flat circular disk set in from the surrounding portion of the plate.

8. In a microphone, the combination of a metal casing comprising a flat wall formed with a central opening and a flange surrounding said opening and forming therewith a cylindrical surface perpendicular to the plane of said wall, and a disk electrode in said opening and affixed at its periphery to said cylindrical surface by a metal binder.

9. In a microphone, the combination of a casing having a wall provided with a smooth cylindrical bore, a cylindrical carbon electrode fitting in said bore, whereby in assembling the parts, the electrode is adjustable in said bore in the direction of its axis, and a metal binder integrally uniting the electrode and casing.

10. In an instrument of the class described, the combination of a main diaphragm formed of glass and responsive to sound vibrations, an electrode, means connecting the electrode to said diaphragm to vibrate therewith, and a mica diaphragm forming a support for the electrode and vibratable therewith, said connecting means comprising a stem extending from the electrode and entering an opening in said main diaphragm, and a cement applied at said opening to unite the stem and diaphragm without producing a tension or strain between the diaphragms.

11. In a telephone instrument, the combination of electrodes having opposing parallel faces spaced apart, a resistance varying medium in the space between said faces, and means for supporting one of said electrodes by its periphery and permitting said electrode during the assembling of the parts to

be adjusted toward or from the other electrode to accurately gage the distance between said opposing faces, and means to fixedly secure the adjusted electrode in said adjusted 5 position.

12. The combination of a microphone casting comprising an outer cylindrical shell and an internal integral web intermediate its ends, said web formed with a central 10 circular opening, and a cylindrical flange forming a continuation of the wall of said opening and providing a cylindrical bearing surface, said flange forming a cylinder within and spaced from said outer shell, 15 and a cylindrical carbon electrode fitted in said opening and having a peripheral bearing therein, the arrangement permitting adjustment of the electrode in an axial direction in assembling, and means to fixedly 20 secure the electrode in adjusted position in the casing.

13. A telephone instrument comprising, in combination, a fixed electrode, a swinging electrode, a variable resistance medium between the electrodes, a diaphragm, and a 25 binder uniting the diaphragm and swinging electrode, said binder consisting of a self-hardening material which may be applied as a liquid, and which when hardened 30 rigidly unites the diaphragm and electrode.

14. In a telephone instrument, the combination of a main diaphragm formed of glass and responsive to sound vibrations, an electrode, means connecting the electrode to 35 said diaphragm to vibrate therewith, said connecting means comprising a material which may be applied as a liquid and which is self-hardening to fixedly unite said diaphragm and electrode, and a second diaphragm forming a support for the electrode and 40 vibratable therewith.

15. In a telephone instrument, the combination of a diaphragm, a vibratable resistance varying element, means to support said element and diaphragm, each independently 45 of the other and permitting each to vibrate, and means to connect said diaphragm and said element to vibrate together, said connecting means comprising a material which 50 may be applied as a liquid and which becomes hard and firmly unites said parts.

16. The combination of an element vibrative in response to impulses applied thereto with a frequency within the range of frequency of sound waves, a vibrative resistance varying element, means for supporting each of said elements independently of the other, and means for connecting said elements to vibrate in unison, said connecting 60 means comprising a cement which may be applied as a liquid and then hardens and fixedly unites said elements.

17. In a sound transforming instrument, a glass diaphragm vibratable in response to 65 sound vibrations impressed thereon, and a

swinging element of a resistance medium co-operatively affixed thereto with a binder consisting of a material applied in a comparatively liquid state as a joint between the same and preventing any material stress or 70 strain between the diaphragm and said swinging element, which binder sets or hardens after application.

18. In a sound transforming instrument, the combination of a thin diaphragm of 75 vitreous material vibrative in response to sound waves impinging thereon, electrical resistance varying means comprising a diaphragm, and means to connect the diaphragms without placing strain thereon 80 while they are at rest, said connecting means comprising a binder applied as a comparatively liquid mass which sets or hardens after being applied.

19. In a telephone instrument, the combination of a casing, sound transforming mechanism therein, and a protector plate secured to the exterior of the casing and substantially covering the back face of the casing, said protector plate comprising a flat 90 body portion spaced a short distance only from the casing, and a surrounding peripheral portion lying against and fixed to the casing adjacent its periphery, said body portion being set in from the surrounding portion and thereby protected from pressure applied to said plate.

20. A sound conveyer or converter, having a disk or plate, concave on the interior and exterior, and comprising a central perforated portion, said interior concavity being provided with an annular groove which surrounds the concavity, and forms a compression chamber for sound waves entering through the central perforations. 100

21. The combination of a diaphragm, an inclosing casing having an annular seat for the diaphragm, said casing comprising a disk or plate in front of the diaphragm and having a perforated central portion for the 110 passage of sound waves to the diaphragm, said plate formed on its inner surface with an annular recess or hollow between the perforated central portion and said seat and serving as a capacity chamber for the sound 115 waves.

22. The combination of a diaphragm, an inclosing casing having an annular seat for the diaphragm, said casing comprising a disk or plate in front of the diaphragm and 120 having a perforated central portion for the passage of sound waves to the diaphragm, the inner surface of said central portion being concave, said plate formed on its inner surface with an annular recess or hollow between the perforated central portion and said seat and serving as a capacity chamber for the sound 125 waves.

23. A sound conveyer or converter, having a disk or plate, concave on the interior and 130

exterior, and comprising a central perforated portion, said interior concavity being provided with an annular groove which surrounds the concavity and forms a compression chamber for sound waves entering 5 through the central perforations, said plate being provided with perforations leading from said annular groove to the outside of the plate.

24. The combination of a diaphragm, an inclosing casing having an annular seat for the diaphragm, said casing comprising a disk or plate in front of the diaphragm and having a perforated central portion for the 10 passage of sound waves to the diaphragm, said plate formed on its inner surface with an annular recess or hollow between the perforated central portion and said seat and serving as a capacity chamber for the sound 15 waves, said plate being provided with perforations leading from said annular recess to the outside of the plate.

25. An instrument comprising a casing, electric current carrying parts or members 20 within the casing, said parts extending into one of the walls of the casing and having electric terminal connectors leading to the outside of the casing, and a protector plate secured to said casing and covering the 25 otherwise exposed electric current carrying members and terminal connectors, said plate lying in close proximity to said wall of the casing to limit the thickness of the instrument, and extending a short distance beyond one edge of the casing and turned back 30 to meet the casing and thereby form a pocket in the protector plate for the reception of cord terminals, said extension terminating in a round lip cord outlet.

26. In a telephone instrument, the combination with a diaphragm, of a plate having openings opposite the central portion of the diaphragm for the passage of sound waves, said openings comprising a central 35 group consisting of three openings arranged in the form of a triangle around the imperforate center of the plate, and openings surrounding the first group, all of the openings being substantially equal in size, each 40 opening of the central group forming with any two of the adjacent surrounding openings a triangular group, the openings of each group being equally spaced, so that the lines joining the centers of the openings in 45 any of said groups form an equilateral triangle, the distance between the openings in each group being substantially equal to or less than the diameter of the openings.

27. In a sound transforming instrument, 50 the combination of a diaphragm, and a protecting plate or web therefor having openings for the transmission of sound waves, said openings being equally spaced, of equal size and closely arranged so that the 55 distance between adjacent openings is substan-

tially equal to or less than the diameter of the openings, each opening forming with two adjacent openings a triangular group, the centers of the openings for each group forming the apexes of an equilateral triangle. 70

28. A protecting plate for a telephone instrument consisting of a plate of a size to fit such instrument having an imperforate center and formed with openings for the transmission of sound waves, said openings being equally spaced, of equal size and closely arranged so that the distance between adjacent openings is substantially equal to or less than the diameter of the openings, each opening forming with adjacent openings a triangular group, the centers of the openings for each group forming the apexes of an equilateral triangle. 75

29. In a sound transforming instrument, the combination of a diaphragm, and a protecting plate therefor having openings for the transmission of sound waves, the walls of said openings being flared to form funnel shaped passages through the plate, said openings comprising a central group of 80 three equally spaced openings surrounding the imperforate center of the plate, and openings surrounding said central group, all of the openings being of equal size, closely arranged and equally spaced, so that 85 each opening forms with adjoining openings a triangular group or groups of equally spaced openings, the distance between the openings in each group being substantially equal to or less than the diameter of the 90 openings.

30. In a sound transforming instrument, the combination with a diaphragm, of electrical resistance varying means comprising a vibrative element, and means to unite said 105 element and diaphragm including a binder which is applied in a liquid state and then allowed to harden.

31. In a sound transforming instrument, the combination with a microphone and a 110 co-acting member therefor having adjoining portions, of a connecting medium consisting of a material which may be applied in a liquid state for fixedly uniting the adjoining portions of said microphone and said co-acting member, so that the microphone and co-acting member will vibrate in unison, said medium consisting of a material which may be applied in a comparatively liquid state, preventing any strain 115 between the microphone and said co-acting member while said parts are at rest.

32. In a sound transforming instrument, the combination with a microphone having a swinging electrode, and a diaphragm, 125 means extending between said electrode and diaphragm by which they are united to vibrate together, said uniting means comprising a material which may be applied as a liquid, but which after it is applied 130

is caused to harden and thereby complete the connection.

33. In an instrument of the class described, a casing comprising working elements or 5 conducting parts and a peripheral wall carrying exposed connecting terminals, of a protector plate secured to said casing and covering the said exposed working elements or conducting parts and the said connecting 10 terminals, said plate having an integral extension at one part of its periphery projecting beyond the edge of the casing and turned back toward the casing so as to form a pocket for cord terminals, said extension terminating a short distance beyond the casing in a round lip cord outlet. 15

Signed at New York, in the county of New York and State of New York this 23rd day of November, A. D. 1914.
